Primary Examiner — Leanne Was-Englehart(74) *Attorney, Agent, or Firm* — Quickpatents, LLC; Kevin Prince(57) **CLAIM**

The ornamental design for an interlocking water-fillable flood barrier, as shown and described.

DESCRIPTION

FIG. 1 is a perspective view of an interlocking water-fillable flood barrier, showing our new design;

FIG. 2 is an enlarged perspective view thereof;

FIG. 3 is a front elevational view of FIG. 2;

FIG. 4 is a rear elevational view of FIG. 2;

FIG. 5 is a top plan view of FIG. 2;

FIG. 6 is a bottom plan view of FIG. 2;

FIG. 7 is a left-side elevational view of FIG. 2; and,

FIG. 8 is a right-side elevational view of FIG. 2.

The broken lines showing a garage door in FIG. 1 depict environmental matter and form no part of the claimed design. The broken lines in FIGS. 7 and 8 depict portions of the water-fillable flood barrier that form no part of the claimed design.
